CLAIM

The ornamental design for a pulsating electromagnetic field generator, as shown and described.

DESCRIPTION

FIG. 1 is a top front perspective view of a pulsating electromagnetic field generator showing my new design;

FIG. 2 is a bottom front perspective view thereof;

FIG. 3 is a top rear perspective view thereof;

FIG. 4 is a bottom rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

In the drawings, the broken lines illustrate portions of the article which form no part of the claimed design.
